Primary Examiner—Philip S. Hyder

(57) **CLAIM**

The ornamental design for a woven wooden briefcase, as shown and described.

DESCRIPTION

FIG. 1 is a top perspective view of a woven wooden briefcase showing my new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a top perspective view of an alternate embodiment of the woven wooden briefcase, wherein the bottom perspective view is identical to FIG. 2;

FIG. 10 is a top perspective view of a second alternate embodiment of the woven wooden briefcase, wherein the bottom perspective view is similar to FIG. 2, the only difference being the corner pieces;

FIG. 11 is a top perspective view of a third alternate embodiment of the woven wooden briefcase, wherein the bottom perspective view is similar to FIG. 2, the only difference being the lack of the wood grain; and,

FIG. 12 is a top plan view of a fourth alternate embodiment of the woven wooden briefcase wherein the rest of the views are identical to FIGS. 2, 3, 4, 6, 7, and 8.
